UNITED STATES PATENT OFFICE

WILLIAM C. CARTER, OF FLINT, MICHIGAN

CARBURETOR

Application filed July 15, 1927. Serial No. 206,030.

This invention relates to carburetors of the type that are equipped with one or more siphoning devices arranged so as to progressively increase the suction on the nozzle or fuel supplying element of the carburetor as the throttle valve is moved into its open position.

One object of my invention is to provide an exceptionally economical carburetor that is particularly adapted for use on high speed, small bore, six-cylinder motors, such as are now used extensively on automobiles.

Another object is to provide a carburetor that will function as a small capacity carburetor at ordinary running speeds, and will function as a large capacity carburetor at high speeds, notwithstanding the fact that it is provided with a fixed liquid fuel supply jet or orifice.

Another object is to provide a carburetor that is equipped with an accelerating well, and means whereby a quick opening of the throttle will discharge the fuel from said well suddenly and virtually dump said fuel into the main passageway, and a slow or gradual opening of the throttle will discharge the fuel from said well gradually and economically, through a path separate and distinct from that through which the fuel escapes from the well on a sudden opening of the throttle.

And still another object is to provide a carburetor of the kind above described that is easy to adjust, reliable in operation and inexpensive to manufacture. Other objects and desirable features of my invention will be hereinafter pointed out.

To this end I have devised a carburetor that is equipped with a well for holding an accelerating charge of liquid fuel which is in readiness to be drawn into the main passageway of the carburetor in the event the throttle valve is opened suddenly; a liquid fuel tube or by-pass leading from a supply of liquid fuel, preferably from the accelerating well, and arranged with its upper end communicating with the main passageway of the carburetor at such a point that it will supply fuel to said passageway at idle speeds and slow speeds, i. e., when the throttle valve is closed,

or only partly open; a fuel supply device, preferably a nozzle provided with a fixed discharge orifice; an air chamber communicating with the main passageway of the carburetor and provided with a fixed air inlet; a plurality of siphoning devices for producing different degrees of suction on the fuel nozzle according to the position of the throttle valve; a means for causing air to be admitted to the stream of liquid fuel passing through the nozzle when the throttle is moved into its wide open position, thereby increasing the supply of fuel to the main passageway by speeding up the flow of the fuel through the nozzle, due to the fact that a stream composed of liquid fuel and some air will travel at a higher speed than a solid stream of liquid fuel; and means for automatically increasing the size of the opening between the air chamber and the main passageway when the speed of travel of the stream of fuel discharging from the nozzle is speeded up or increased by admitting air to said stream.

A carburetor of the construction above described virtually acts as a small capacity carburetor at ordinary running speeds, but when the throttle valve is moved into its high speed position, the suction of the motor causes the supply of fuel and the supply of air to the main passageway to be increased to such an extent that the carburetor is converted into a large capacity carburetor, notwithstanding the fact that the fuel nozzle is provided with a fixed orifice or jet. The various elements that make up the carburetor can be constructed and arranged in various ways without departing from the spirit of my invention, but I prefer to locate the accelerating well at the lower side of the air chamber in longitudinal alignment with the main passageway and arrange the fuel nozzle in said well so that it discharges upwardly towards said main air passageway. A plurality of concentrically arranged, tubular members of different diameters are combined with the nozzle in such a way as to produce siphoning devices that exert different degrees of suction on the nozzle at different stages of speed of the motor.

Figure 1 of the drawings is a vertical sec-

tional view of my improved carburetor, showing the throttle valve in its high speed or wide open position.

Figure 2 is a fragmentary vertical section view, showing the throttle valve in its closed position; and

Figure 3 is a sectional view, taken on the line 3—3 of Figure 1.

In the accompanying drawings which illustrate the preferred form of my invention, embodied in a carburetor of similar design and embodying some of the features of the carburetor described in my pending application for Patent Serial No. 147,010, filed November 8, 1926, A designates the main passageway of the carburetor, which is arranged vertically, B designates the throttle valve in said passageway, C designates an air chamber that communicates with the lower end of said main passageway, C' designates a fixed air inlet to said air chamber, D designates a conventional choke valve for the air chamber, E designates the float chamber of the carburetor, F designates an annular float in the float chamber that surrounds a depending, hollow portion 1 on the body casting of the carburetor that constitutes an accelerating well G, and H designates a needle valve that governs the admission of fuel to the float chamber from a source of supply of liquid fuel, said needle valve being preferably of triangular shape in cross section, as shown in Figure 3, and combined with an operating lever H' that is adapted to be actuated by the float F. The carburetor is equipped with a fuel duct or by-pass that leads upwardly from the accelerating well G and which is used to supply fuel to the main passageway A when the throttle valve is closed or only partly open. Said fuel duct or by-pass can be constructed in various ways, but it is preferably of the construction illustrated and described in my pending application previously referred to and comprises an upper portion formed by a straight, vertically-disposed tube 2 that projects downwardly through the portion of the body casting in which the main passageway A is formed and terminates in a lug 3, the lower end of said fuel duct or by-pass being formed by a vertically-disposed groove 4 in the exterior of a sleeve 5 that is snugly surrounded by the side wall of the accelerating well G. The sleeve 5 is spaced away slightly from the bottom of said well and the lower end of the groove 4 is open, so that fuel can flow upwardly through said groove from the supply of fuel in the accelerating well.

The upper end portion of the fuel tube 2 is so constructed, formed or arranged that when the throttle valve is closed or only partly open, fuel will pass from the upper end of said tube into the passageway A at a point above the throttle valve and sufficient air will enter said tube from the passageway

A at a point below the throttle valve to cut down or reduce the suction that is exerted on the upper end of the tube 2 by the high vacuum which then exists in the intake of the motor. The upper end portion of the tube 2 is also designed so that the movement of the throttle valve forwardly, away from its idle position, cuts off the admission of the air that reduces the suction in said tube, thereby causing the full force of the suction which exists in the intake to become effective for drawing fuel upwardly through the tube 2. The result above described can be accomplished in various ways, but in the carburetor herein illustrated a hole 2^a is formed in the side of the tube 2 at a point far enough below the upper end of said tube to cause the hole 2^a to be located below the throttle valve, as shown in Figure 2, when said throttle valve is in its closed position.

The lug 3 in which the lower end of the tube 2 is seated is provided with an air passageway 6 through which air is admitted to the lower end of the tube 2 from the air chamber C, and in order that the supply of air through said air passageway 6 may be regulated, an adjustable valve 7 is provided for controlling the admission of air to the air passageway 6. Said air regulating valve 7 is herein illustrated as being provided with a stem having an externally-screw-threaded portion that is screwed into a hole in the lug 3 which communicates with the upper end of the fuel duct or groove 4 that leads upwardly from the accelerating well, and the valve 7 is preferably provided with a spring or other suitable device 8 for retaining said valve in adjusted position. As shown in Figure 1, the stem of the air valve 7 is provided with a fuel duct 9 that has a lateral outlet which constitutes a fuel supply orifice for the air passageway 6. When the engine is idling with the throttle valve set in its closed position, liquid fuel, mixed with air, will be drawn upwardly through the tube 2, and discharged from the upper end of said tube into the main passageway A at a point above the throttle valve, due, of course, to the fact that the vacuum in the intake of the motor produces a suction in the tube 2 that is exerted on the fuel duct or port 9 in the stem of the air valve 7. Notwithstanding the fact that the tube 2 establishes direct communication between the intake of the motor and the fuel supply duct 9 in the stem of the air valve when the throttle valve B is in its idle position, only a relatively slight suction exists in the tube 2, because air is entering the lower end of said tube from the air passageway 6 and air is entering the upper end of said tube 2 through the lateral opening 2^a in said tube, which, at this time, is located below the throttle valve. After the throttle valve has been moved into such a position that the opening 2^a in the upper end portion

of the tube 2 will be positioned above the throttle valve, the high vacuum which exists in the intake of the motor when the throttle valve is only partly open will become operative for drawing fuel upwardly through the tube 2, thus increasing the amount of fuel which said tube introduces into the passageway A.

A fuel nozzle I is arranged vertically at the center of the accelerating well G with its discharge end directed upwardly towards the main passageway A, and a fuel duct or port 10 of relatively large diameter is used to admit liquid fuel from the float chamber E to a center bore 11 in a plug 12 in the bottom of the accelerating well that carries the nozzle I, the duct or fuel passageway 13 of the nozzle I communicating with the center bore 11 in the plug 12. A duct 14 of considerably less cross-sectional area than the supply port 10 is formed in the plug 12 in such a way that the upper end of said duct 14 communicates with the accelerating well G and the lower end of said duct communicates with the center bore 11 in the plug previously referred to. The nozzle I is provided intermediate its ends with a transversely-disposed duct or cross duct 15 which establishes communication between the accelerating well and the center passageway 13 of the nozzle, and below said duct is a contracted portion 13^a whose lower end or inlet end is flared at 13^b so as to overcome the tendency of said contracted portion to clog, as hereinafter described. The fuel in the float chamber E normally stands at the level indicated by the broken line α in Figure 1, and accordingly, there is normally an accelerating charge in the well G that is in readiness to be drawn into the main passageway A of the carburetor in the event the throttle valve is opened suddenly.

Normally, the duct 14 functions as a fuel supply duct to admit liquid fuel to the accelerating well from the bore 11 in the plug 12, the weight of the fuel in the float chamber causing the fuel to pass upwardly through the port 10 into the bore 11, and thence upwardly into the accelerating well through the duct 14. As the speed of the motor increases, the suction in the bore 11 increases, and when the suction in said bore 11 balances the weight of the fuel in the float chamber, the duct 14 becomes neutral, or ceases to supply liquid fuel to the accelerating well. Thereafter, as the speed of the motor builds up, the suction in the bore 11 increases to such an extent that air will be drawn downwardly through the duct 14, and thence upwardly into the funnel-shaped inlet end of the center passageway 13 of the nozzle, thereby increasing the speed of travel of the fuel through the contracted portion 13^a of said center passageway 13.

65 The plurality of concentrically-arranged,

tubular siphoning devices, previously referred to, that are combined with the nozzle I so as to exert different degrees of suction on said nozzle in different positions of the throttle valve, are herein illustrated as being formed by a tubular member J, preferably of Venturi form, projecting upwardly from the bottom of the accelerating well in concentric relation with the fuel nozzle I and arranged with its contracted portion located adjacent the upper end of said nozzle, a second tubular member K attached to the upper end of the sleeve 5 in the accelerating well, and preferably shaped so as to form a Venturi whose contracted portions surrounds the upper end of the tubular member J, and a third tubular member L, preferably of Venturi form, arranged in the main passageway A with its contracted portion normally positioned in close proximity to the upper end of the tubular member K. While I prefer to make said tubular members of Venturi form, this is not essential, so long as a bottom tubular member is combined with the upper end portion of the fuel nozzle I in such a way as to form an annular passageway up through which air will rush, and thus create a suction on the upper end of the fuel nozzle, a second or intermediate tubular member is combined with the upper end of the bottom tubular member first referred to, so as to form a second annular passageway up through which air rushes, thus creating a strong suction inside of the first tubular member, and a third or top tubular member is combined with the upper portion of the intermediate tubular member in such a way as to form an annular passageway up through which air rushes, and thus creates a strong suction inside of the second tubular member.

The tubular member L, referred to above as the third or top member, is mounted in the main passageway A in such a manner that it is capable of moving vertically relatively to the tubular member K, so as to vary the size of the annular opening between the contracted portion of the member L and the upper end of the member K through which air passes from the air chamber C to the main passageway A, and also vary the operation of the separate passageway, formed by the bottom and intermediate siphoning devices through which a mixture of air and fuel enters the main passageway. In the carburetor herein illustrated the reciprocating movement of the member L in opposite directions is limited by one or more stops 16 formed preferably by a screw or screws that project inwardly from the side wall of the passageway A into an annular groove 17 in the exterior of the member L, but I wish it to be understood that various other means can be used for increasing the supply of air from the air chamber to the main passageway

A of the carburetor without departing from the spirit of my invention.

Air openings 18 are formed in the sleeve 5 adjacent the contracted portion of the siphoning device K, so as to admit air to the accelerating well and to the annular space at the upper end of the member J, and a plurality of vertically-disposed slots 19 are formed in the lower end portion of the member J, so as to admit air and liquid fuel to the interior of said member, from the accelerating well, said slots extending upwardly from the bottom of the accelerating well G.

As previously stated, the tube or by-pass 2 supplies fuel to the main passageway A when the motor is idling and also when the throttle valve is partly open, the particular period in the cycle of operations of the carburetor when the tube 2 goes out of service, or, in other words, when said tube ceases to supply fuel to the passageway A, varying. Usually, however, the tube 2 will go out of service when approximately 10% of the capacity of the carburetor is reached. From this point on, the fuel in the accelerating well G and the fuel discharged from the nozzle I constitutes the source of supply of fuel for the main passageway A. After the throttle valve has reached such a position that the tube 2 ceases to supply fuel to the passageway A, the air that is drawn upwardly into said passageway through the annular opening between the upper end of the tubular member K and the contracted portion of the tubular member L, which, at this time is in the position shown in Figure 2, creates a suction inside of the bottom tubular member J of sufficient intensity to draw air inwardly through the openings 18 in the sleeve 5, thence downwardly into the well G and through the vertically-disposed slots 19 in the lower end of the member J, and thereafter, upwardly through said member J, thus causing more or less of the fuel in the well G to be absorbed by the air and carried upwardly into the main passageway A. When the throttle valve reaches such a position as to cause sufficient air to travel through the well G to keep said well dry, the suction inside of the intermediate tubular member K becomes strong enough to cause air to be drawn inwardly through the openings 18 in the sleeve 5, and thence upwardly through the annular space between the upper end of the tubular member J and the lower end of the intermediate tubular member K. The air that rushes upwardly through said annular space increases the suction inside of the bottom tubular member J, and causes fuel to be drawn from the nozzle I and carried upwardly into the main passageway A.

Up to this stage of speed the carburetor functions as a small capacity carburetor, but the movement of the throttle valve B into its wide open position automatically converts the

carburetor into a large capacity carburetor by permitting the motor to increase the supply of air through the main passageway A and simultaneously increase the supply of liquid fuel to said main passageway A. The increase in the supply of air to said passageway is obtained by mounting the siphoning device L in the passageway A in such a manner that the inrush of air into the passageway A causes the member L to move upwardly away from the upper end of the member K, as previously described, thereby increasing the size of the opening through which air is admitted to the passageway A from the air chamber C. The increase in the supply of liquid fuel to the main passageway A is obtained by exerting a stronger suction on the fuel nozzle I and also by causing air to be admitted to the center duct or passageway 13 of said nozzle, so as to speed up the flow of the fuel that travels upwardly through said nozzle, it being a well established fact that a stream of liquid fuel which contains some air will travel at a higher speed than a solid stream of liquid fuel, assuming, of course, that both streams are subjected to a suction of the same degree or intensity. In the form of my invention herein illustrated the admission of air to the center duct or passageway 13 of the fuel nozzle I is obtained by drawing air downwardly through the duct 14, and thence upwardly through the contracted portion 13a of the center passageway of the fuel nozzle, which action is produced by increasing the suction that is exerted on said nozzle, due to the air rushing upwardly through the annular space between the upper end of the nozzle I and the contracted portion of the bottom tubular member J. When the carburetor is functioning in this manner, i. e., as a large capacity carburetor, a considerably greater quantity of air is rushing upwardly past the upper end of the intermediate tubular member K, and air is also rushing upwardly past the upper end of the bottom tubular member J. At this time air is also rushing upwardly around the upper end of the fuel nozzle, the air that rushes upwardly past the end of the nozzle being admitted to the interior of the lower end portion of the bottom tubular member J through the vertical slots 19 in same.

From the foregoing it will be seen that in a carburetor of the construction above described there is one stage in which the air that rushes upwardly around the upper end of the tubular member K produces sufficient suction inside of said member to cause air to travel through the accelerating well G and keep said well dry; there is another stage in which the air that rushes upwardly around the upper end of the bottom tubular member J produces sufficient suction inside of said member J to cause fuel to be drawn from the nozzle I and discharged upwardly

into the main passageway A; and there is still another stage in which the air that rushes upwardly around the end of the nozzle I produces a considerably stronger suction on the center duct 13 of said nozzle and also causes air to break into or mix with the stream of liquid fuel that is flowing upwardly through said center duct.

When the throttle valve is moved back towards its closed position the tubular member L in the main passageway A drops back to its normal position shown in Figure 2, thereby concentrating the suction on the tubular members which are arranged in a lower plane and causing said lower tubular members to draw fuel until the throttle valve reaches a position where the by-pass 2 begins to deliver fuel, and continuing until the throttle valve reaches its position set for idle. By equipping the carburetor with elements of the kind and arrangement above described I obtain a carburetor of small capacity when the tubular member L is in its lower position and the by-pass 2 is functioning, and I obtain a carburetor of great capacity when the tubular member L is in its high position and the multiple siphoning devices are functioning to deliver fuel in an advance relation to the flow of air.

To put it in another way, when the throttle valve is moved back towards its closed position, the flow of gas through the carburetor diminishes, and for lack of support, the tubular member L drops downwardly towards its position of rest shown in Figure 2. The annular passage between the lower end of the member L and the top of the intermediate member K being reduced, the diminished flow of gas is concentrated in the annular space between K and J, and between J and the nozzle I, to thus maintain a more robust activity at these critical points and compensate for the fuel flow to lag behind the air flow as the suction diminishes. As the throttle valve continues to move towards its closed position, the upward flow of air between the upper end of the tubular member J and the contracted portion of the intermediate member K ceases, and when the throttle valve is near its idling position, the fuel tube or by-pass 2 comes into service and supplies fuel directly to the main passageway A at a point in proximity to the throttle valve.

It is necessary that the contracted portion 13^a of the fuel duct 13 of the nozzle I be of very small diameter, so that said nozzle will not supply too much fuel when the throttle valve is in its wide open position, and in order to prevent the contracted portion of said duct 13 from becoming clogged by the small particles of lint that are invariably present in gasoline, and which might become arranged transversely across the lower end of a small bore duct of uniform diameter

and clog the same, I enlarge or flare the lower end portion of the duct 13 in the nozzle, as indicated by the reference character 13^b in Figure 1, so that if particles of lint or fine hair-like pieces of foreign matter become arranged crosswise of the lower end of the fuel passageway of the nozzle I, the suction at the upper end of the nozzle will cause said particles of lint or the like to fold or double up in the flared inlet portion 13^b of the fuel duct of the nozzle and then travel upwardly through the contracted portion of said fuel duct, with the fuel. The cross duct 15 in the nozzle I enables the diameter of the contracted portion 13^a of the center duct 13 of the nozzle to be made larger than would be possible if the cross duct 15 were omitted, due, of course, to the fact that the air which is drawn inwardly through said cross duct reduces the suction that is created on the contracted portion 13^a.

As previously stated, one object of my invention is to provide a carburetor that has an accelerating well and which is of such construction that a sudden opening of the throttle will cause the fuel in said well to be dumped into the main passageway of the carburetor, and a slow or gradual opening of the throttle will cause the fuel in the accelerating well to be discharged gradually and economically through a path separate and distinct from that through which the fuel escapes from the accelerating well on a sudden opening of the throttle. In the form of my invention herein illustrated the sudden discharge of the fuel from the accelerating well, or the dumping of said fuel into the main passageway of the carburetor, is effected by forming vertically-disposed slots 19 in the lower end portion of the tubular member J that surrounds the fuel nozzle. When the throttle is opened suddenly, the air that rushes downwardly into the accelerating well picks up the fuel in said well and carries it inwardly through the slots 19 in the tubular member J, and thence upwardly through said tubular member into the main passageway A. The gradual and economical discharge of the fuel from the accelerating well is effected by arranging the duct 14 at the lower end of the accelerating well in such a way that it establishes communication between said well and the lower end of the center passageway 13 of the fuel nozzle. When the throttle is opened gradually, the steady suction that is exerted on the upper end of the fuel nozzle causes the fuel in the accelerating well to be drawn slowly or gradually, downwardly through the duct 14, and thence upwardly through the center passageway of the fuel nozzle. Consequently, a carburetor of the construction above described is distinguished from conventional carburetors of the type that are equipped with accelerating wells, in that two paths are provided for the escape

of the fuel from the accelerating well, one path being so constructed that the fuel can escape rapidly, practically in one large gulp, to use a homely phrase, and the other path being so constructed that the fuel will escape gradually, which, of course, adds greatly to the economy of the carburetor.

A carburetor of the construction above described is exceptionally efficient and economical and is particularly adapted for use on high speed, small bore, six-cylinder motors, due to the fact that it functions as a small capacity carburetor at ordinary running speeds and functions as a large capacity carburetor at high speeds, notwithstanding the fact that the fuel nozzle has a fixed orifice or duct. The carburetor is easy to adjust, it is reliable in operation and it is of such design that there are no abrupt variations in the fuel supply between successive stages of speed of the motor. In addition to the desirable features above pointed out, the carburetor above described is inexpensive to manufacture, as it is composed of a relatively small number of parts that can be produced by simple machine operations and thereafter assembled easily.

Having thus described my invention, what I claim as new and desire to secure by Letters Patent of the United States is:

1. A carburetor for an internal combustion motor, provided with a main passageway through which a mixture of fuel and air travels to the intake of the motor, a throttle valve for said main passageway, an accelerating well for holding fuel, means for causing the fuel in said well to be dumped into said main passageway when the throttle is opened suddenly, and a separate and distinct means for causing the fuel to be discharged from said well into the main passageway gradually and economically when the throttle is opened gradually.

2. A carburetor for an internal combustion motor, provided with a main passageway through which a mixture of fuel and air travels to the intake of the motor, a throttle valve for said main passageway, an accelerating well for holding fuel, two separate and distinct paths of travel for the fuel from said well to said passageway, one of said paths being so proportioned that the fuel will travel through same freely when the throttle is opened suddenly and the other being so proportioned that a gradual opening of the throttle causes the fuel in said well to pass gradually into said main passageway.

3. A carburetor for an internal combustion motor, provided with a main passageway through which fuel and air travel to the intake of the motor, a throttle valve for said main passageway, an idle feed fuel supplying means for delivering fuel to said passageway above the throttle valve, an air chamber provided with a fixed air inlet, an

accelerating well for holding fuel, a tubular member leading from said well and arranged so as to discharge into said main passageway, a shiftable member in the main passageway that co-operates with the upper end of said tubular member to form a variable air inlet for the main passageway that is always open, and two separate and distinct paths through which the fuel in the accelerating well can travel from said well into said main passageway, one of said paths being of considerably greater cross-sectional area than the other so as to permit the fuel in the accelerating well to be discharged from same quickly by a sudden opening of the throttle or discharged gradually by slowly opening the throttle.

4. A carburetor for an internal combustion motor, provided with a main passageway through which a mixture of fuel and air travels to the intake of the motor, a throttle valve in said passageway, means for supplying fuel to said passageway above the throttle valve for idle speeds, a fuel nozzle arranged so as to discharge fuel towards said passageway, a tubular element arranged in concentric relation with said nozzle and provided intermediate its ends with an air inlet, a shiftable member in said main passageway operated by the suction of the motor, that co-operates with the upper end of said tubular element to form a variable air inlet for said main passageway, an accelerating well formed by the lower portion of said tubular element, a Venturi member in said well surrounding said nozzle and arranged with its contracted portion located adjacent the upper end of the nozzle and with its upper end located adjacent the air inlet of said tubular element, and an air inlet in the lower end portion of said Venturi member.

WILLIAM C. CARTER.
